CLAIM

We claim the ornamental design for a coffee dripper, as
shown and described.

DESCRIPTION

FIG. 1 is a top perspective view of a coffee dripper in
accordance with the present design;

FIG. 2 is a right side view thereof;

FIG. 3 is a left side view thereof;

FIG. 4 is a front view thereof;

FIG. 5 is a rear view thereof;

FIG. 6 is a top view thereof;

FIG. 7 is a bottom view thereof; and,

FIG. 8 is a cross-sectional view taken along line **8-8** of FIG.

6.

The broken lines show parts of the article which form no part
of the claimed design.

1 Claim, 5 Drawing Sheets
